DESIGN FOR AN EYEGLASS FRAME OR SIMILAR ARTICLE

Raymond L. Wells, Attleboro, Mass., assignor to
American Optical Company, Southbridge,
Mass., a voluntary association of Massachu-
sets

Application July 18, 1936, Serial No. 63,933

Term of patent 14 years

To all whom it may concern:

Be it known that I, Raymond L. Wells, a citizen of the United States of America, residing at Attleboro, in the county of Bristol and State of Massachusetts, have invented a new, original, and ornamental Design for an Eyeglass Frame or Similar Article, of which the following is a specification, reference being made to the accompanying drawing forming a part thereof.

Fig. I is an enlarged perspective view of an eyeglass frame or similar article embodying my new design;

Fig. II is a plan view of the mounting shown in Fig. I; and

Fig. III is a segment of one of the rims on an enlarged scale.

The characteristic features of my design are shown in full lines. The parts shown in dotted lines are of conventional form.

I claim:

The ornamental design for an eyeglass frame or similar article substantially as shown and described.

RAYMOND L. WELLS.
